UNITED STATES PATENT OFFICE.

ERNEST M. HAUBER, OF HAMMOND, INDIANA.

PAPER-LIFTER.

1,134,848.

Specification of Letters Patent.

Patented Apr. 6, 1915.

Application filed August 21, 1914. Serial No. 857,906.

To all whom it may concern:

Be it known that I, ERNEST M. HAUBER, a citizen of the United States, residing at Hammond, in the county of Lake and State 5 of Indiana, have invented certain new and useful Improvements in Paper-Lifters; and I do hereby declare the following to be a full, clear, and exact description of the invention, such as will enable others skilled 10 in the art to which it appertains to make and use the same.

This invention has for its object to provide a simple and efficient paper lifter conveniently attachable to standard types of 15 paper roll supports for lifting the end of the paper into position where it may be conveniently grasped.

Another object is the provision of a paper lifter formed substantially of a single piece 20 of wire and including a reinforcing member formed of sheet metal.

With these and other objects in view, the invention consists in the novel construction, arrangement and formation of parts as will 25 be hereinafter specifically described, claimed and illustrated in the accompanying drawings, in which:

Figure 1 represents an end elevation of a roll of paper mounted in the usual supports, 30 showing the application of my improved paper lifter thereto. Fig. 2 represents a perspective view of the bracing and reinforcing member of the lifter removed. Fig. 3 represents a front elevation, partly broken 35 away, of the supports and paper roll, showing the paper lifter attached, and Fig. 4 represents a horizontal sectional view on a line 4—4 of Fig. 3.

Referring to the drawing in detail, where- 40 in similar reference numerals designate corresponding parts, throughout the several views, the numeral 5 indicates the paper lifter which is preferably formed from spring wire of adequate thickness, one end 45 6 of which is looped, as indicated at 7, and the adjacent end portion extended parallel with the end portion 6 and coiled at 9 around the end 6. From the coil 9 the wire is extended upwardly, thence turned down- 50 wardly to provide a loop 10 having the upper edge 11 beveled to engage beneath the edge of the paper, as will be hereinafter clearly apparent. From the loop 10 the end 55 of the wire 12 is extended through the coil 9 and is twisted at 13 about the end 6 and the adjacent parallel portion 8.

A substantially L-shaped bracing and reinforcing member 14, preferably formed from sheet metal, is formed at one end with an opening 15 to receive the portions 6 and 8 60 of the wire, while the opposite end is provided with a pair of spaced parallel openings 16 receiving the parallel portions of the loop 10.

In use, the lower loop 7 is engaged under 65 one standard or support 17 for the roll of paper 18 and is secured in operative position by the screws 19 by means of which the standard or support 17 is anchored in position. The tension of the wire from which 70 the lifter is formed carries the beveled edge 11 thereof into frictional engagement with the periphery of the roll of paper 18, and when said roll is turned, said beveled edge engages beneath the free end 19 of the paper 75 and guides it outwardly into position to be conveniently grasped by the fingers of the operator, as clearly shown in Fig. 1. The coiled portion 9 of the wire from which the lifter is formed increases the tension of the 80 loop 10 against the roll 18 and insures said loop to follow the outer surface of said roll of paper as the latter is used. The L-shaped member 15 materially increases the strength 85 and rigidity of the entire device, and especially the loop 10.

What I claim is:

1. A paper lifter formed from a single piece of spring wire including a looped base portion, an upstanding looped portion having 90 its upper edge beveled, and the intermediate portion coiled to increase the tension of the upstanding looped portion.

2. A paper lifter comprising a looped base portion, an upstanding looped roll-engaging 95 portion, means for normally retaining said upstanding looped portion against a roll of paper, and an L-shaped member for bracing said upstanding looped portion.

3. A paper lifter comprising a looped base portion, an upstanding looped portion having its edge beveled and the intermediate portion coiled to increase the tension of the upstanding looped portion, and an L-shaped member for bracing said upstanding looped 105 portion.

4. A paper lifter including a looped base portion, an upstanding looped roll-engaging portion having its edge beveled, and an L-shaped member for bracing said upstanding 110 looped portion.

5. A paper lifter comprising a looped base

- portion, an upstanding looped roll-engaging portion, and an L-shaped member connecting the looped base portion with the upstanding looped portion to brace the latter.
- 5 6. A paper lifter including a piece of spring wire including a looped base portion, an upstanding looped roll-engaging portion, an L-shaped member connecting said looped base portion with said upstanding roll-engaging portion, said wire being coiled inter-
- 10

mediate the ends of said L-shaped member to increase the tension of the upstanding roll-engaging portion.

In testimony whereof I affix my signature in presence of two witnesses.

ERNEST M. HAUBER.
